United States Patent Office

Des. 179,874

Patented Mar. 19, 1957

179,874

ENVELOPE OF AN ELECTRONIC DISCHARGE DEVICE

William R. Aiken, Berkeley, Calif., assignor, by mesne assignments, to Kaiser Aircraft & Electronics Corporation, a corporation of New York

Application May 12, 1954, Serial No. 30,429

Term of patent 14 years

(Cl. D26—14)

FIG. 1

FIG. 2

Figure 1 is a perspective view of the envelope of an electronic discharge device embodying my new design.

Figure 2 is an end elevational view thereof.

I claim:

The ornamental design for an envelope of an electronic discharge device, substantially as shown.
